UNITED STATES PATENT OFFICE.

PAUL W. STEINBECK, OF NEW HAVEN, CONNECTICUT, ASSIGNOR TO
ELECTRIC VEHICLE COMPANY, OF JERSEY CITY, NEW JERSEY, A
CORPORATION OF NEW JERSEY.

DESIGN FOR AN AUTOMOBILE-BODY.

No. 37,929.

Specification for Design.

Patented March 27, 1906.

Application filed January 3, 1906. Serial No. 294,478. Term of patent 14 years.

To all whom it may concern:

Be it known that I, PAUL W. STEINBECK, a citizen of the United States, residing in the city and county of New Haven, State of Connecticut, have invented a new, original, and ornamental Design for an Automobile-Body, reference being had to the accompanying drawing, in which the figure is a side elevation, partly in perspective, of my newly-designed automobile-body.

What I claim is—

The ornamental design for an automobile-body as shown.

PAUL W. STEINBECK.

In presence of—

J. L. BROCKETT,
P. A. PORTER.
